US0D1070997S

(12) United States Design Patent (10) Patent No.: US D1,070,997 S
(45) Date of Patent: * Apr. 15, 2025

(54) GAMING MACHINE

(71) Applicant: Aristocrat Technologies, Inc., Las Vegas, NV (US)

(72) Inventors: Bruce Urban, Las Vegas, NV (US); Rena Schoonmaker, Las Vegas, NV (US); Ariel Turgel, San Francisco, CA (US); Wei Gu, Daly City, CA (US); Steven Wong, Las Vegas, NV (US)

(73) Assignee: Aristocrat Technologies, Inc., Las Vegas, NV (US)

() Term: 15 Years

(21) Appl. No.: 29/941,255

(22) Filed: May 8, 2024

(57) CLAIM

The ornamental design for a gaming machine, as shown and described.

DESCRIPTION

FIG. 1 is a perspective view of a gaming machine showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In these drawings, the solid lines illustrate the claimed ornamental design, whereas broken lines illustrate unclaimed environmental features and form no part of the claimed design.

1 Claim, 7 Drawing Sheets
